UNITED STATES PATENT OFFICE.

WILLIAM DE COURCY PRIDEAUX, OF WEYMOUTH, ENGLAND.

MAGAZINE FOR HOLDING REVOLVER-CARTRIDGES AND FOR LOADING SAME INTO REVOLVER-BARRELS.

1,181,034.

Specification of Letters Patent. Patented Apr. 25, 1916.

Application filed July 20, 1915. Serial No. 40,951.

To all whom it may concern:

Be it known that I, WILLIAM DE COURCY PRIDEAUX, a subject of the King of Great Britain, residing at Weymouth, Dorsetshire, England, have invented certain new and useful Improvements in Magazines for Holding Revolver-Cartridges and for Loading Same into Revolver-Barrels, of which the following is a specification.

10 This invention relates to the magazine for holding revolver cartridges and for loading same into revolver barrels described and shown in the specification and drawings of my British Letters Patent No. 3560 of 1893 and U. S. Patent No. 516,942, and consists in various improvements in same, whereby certain defects can be avoided and the article rendered more secure in use.

For the purpose of my present invention 20 I provide means for preventing the portion having the springs or clips from being easily removed from the openworked disk, and for positively releasing the cartridges from the magazines when they have been placed in 25 their chambers in the revolver, also for preventing the cartridges shifting in or falling from the magazine while being carried, also for preventing premature explosion of any cartridge should a loaded magazine fall to 30 the ground from any cause and I may provide means whereby a loaded magazine can be carried by a hook or means other than a pouch, and I also may provide means whereby the cartridges can be easily inserted 35 into the barrels with a less amount of friction and also means for preventing the springs holding the cartridges from leaving the disk portion while the cartridges are being or have been inserted into the barrels.

40 My invention will be clearly understood from the following description aided by the annexed drawings in which:—

Figure 1 is a sectional elevation of a complete appliance showing the means for preventing the springs leaving the disk, the disk being constructed for placing the cartridges in cone formation. Fig. 2 is an elevation of the springs and disk with means for retaining the disk and opening out 45 the springs to free the cartridges just when they come fully home in the barrels. Fig. 3 is a plan of the disk. Fig. 4 is a sectional elevation of a device and showing the means for protecting a loading magazine and 50 means for carrying same. Fig. 5 is a sec-

tional elevation of a modified construction of springs as attached to a disk. Fig. 6 is a perspective elevation showing the magazine in position ready for insertion into a Colt or Smith and Wesson revolver. Fig. 7 is a 60 perspective elevation of a charged cartridge magazine and showing a method of charging the cartridges.

As an example of carrying my invention into effect and to prevent the portion having the springs leaving the disk while the cartridges are being inserted into the revolver barrels, I form the tips of the outer ring of springs or clips 1 or it may be the inner ring 2 or both with projections or catches 3, 4, see Fig. 1, which when the disk 5 is pushed along the springs 1, 2 to eject the cartridges held by them, engage the edges 6, 7 of the slots or holes 8, 9 in the disk through which they pass and prevent 65 any separation of the two elements, or I may slot at 10 the outer springs 1, see Fig. 2, along a greater portion of their length and provide the edges 11 of the slots through which they pass with projections 12 which 70 pass through the slots and as the disk is pushed along the springs 1 will engage the projections 12 at the edges of the slots and hold the springs and disk together, and by placing such projections at an angle they 75 will form means for opening out the springs 1 and free the cartridges just as they are 80 fully pushed home into the barrels. I may provide the base 13 of the springs 1, 2 with a post 14 see Fig. 4, centrally situated between the springs and passing through the hole 9 in the disk 5 the end of the post 14 85 being provided with a head or stop 15 against which the disk 5 has action when 90 pushed to its farthest extent and so prevent 95 the cartridge leaving the magazine while being carried.

Instead of slotting the springs 1, 2 I may form grooves 16 in them, see Fig. 5, and provide the disk 5 with projections 17 which 100 ride in the grooves 16 so that as the disk 5 is nearing the end of its movement the projections 17 will ride over the flat portion 18 of the springs and push them outward.

I provide a skeleton or other plate or cup 105 shaped device 19, see Fig. 4, to cover the noses of the bullets and this may be attached to the rod 14 by any suitable means such as a screw stem 20 entering a screw cup shaped head 15 as shown in Fig. 4, or 110

by a spring clip engaging under the head of the rod, but in such a manner so that the protector device can be readily removed by hand before the magazine is to be used, or it 5 may have hooked fingers to engage in the beforementioned slots in the outer ring of clips.

To prevent premature explosion of the cartridges due to a magazine falling or 10 otherwise I form a hole or recess 21 in each disk 5 at the parts where the cap or striking point of the cartridge is situated when in the magazine, so that there is a space thereat whereby any concussion due to falling of a 15 magazine will not be communicated to the cap or striking point.

I may dispense with the ring surrounding the disk and preferably thicken the edge of the disk to form a finger hold or I may 20 form a shallow tip to said disk instead of the deep tip as shown in my previous patent.

To carry the appliance I may provide the disk, cup shaped protector 19 or other part 25 with a hook or ring 22 by which it can be attached to a belt, bandoleer or other article connected to the person.

To enable the cartridges to be easily and 30 readily inserted into the barrels with a less amount of friction I form the disk 5 at the part 28 on which the cartridges rest of slightly cone shape, see Figs. 4 and 5, or I 35 position the clips or springs as a cone, or both, so that the cartridges are held in the 40 appliance in cone formation and as such cartridges are being inserted in the barrels the bullets will first have action against the inside or outside portions of the walls of the barrels and on a further pushing in of 45 the cartridges they will be straightened out to follow the barrels and in doing so each cartridge will be freed from either the inside or the outside springs and so reduce friction whereby less exertion is required to push the cartridges home in their barrels.

In addition to the projections 3, 4 for 50 preventing the spring holding the cartridge leaving the disk portion, when the cartridges are being or have been inserted, I may provide further means on or to the disk to further assist in limiting the movement of the spring portion. Various devices can be employed. For instance I may employ a bridge 23 with its two members 24, 25 secured 55 to the disk portion 5 the bridge 23 forming the means for assisting in limiting the movement of the springs portion as shown at Fig. 1 or I may employ a ring having two or more legs which are secured 60 to the disk, the ring forming the means for assisting in limiting the springs portion, and such bridge or ring may have a loop 22 for attachment of a cord by which the appliance can be suspended and carried on the 65 person. Thus the bridge or ring in conjunc-

tion with the projections or the tips 3, 4 of the springs 1, 2 effectually holds the disk portion 5 and springs together without fear of their being disunited under any circumstances or of either of the spring tips 3, 4 70 getting behind the disk.

I may position a coiled spring 26 between the springs base and the bridge 23 or ring, see Fig. 1, to assist in holding the springs base and cartridges in position while 75 being carried. The coiled spring by keeping the springs base in place against the disk assists in allowing of easy insertion of the cartridges between the springs fingers.

To allow of easy insertion of each cartridge and to obviate the necessity of placing them between the ends of the springs and pushing them down I reduce the width of each outer spring 1, as at 27, see Fig. 7, and I press the cartridge between each two outer 85 springs, the rim of the cartridge finding a position between the recessed portions.

What I claim and desire to secure by Letters Patent is:—

1. In a cartridge holding magazine, a 90 base, a series of tongues projecting from said base between which the cartridges are adapted to be placed, a cartridge ejecting member slideable along the length of said tongues, and coöperating means on said 95 ejecting member and tongues for preventing accidental or easy removal of said ejecting member from said base and tongues.

2. In a cartridge holding magazine, a 100 plurality of tongues fixed relatively with respect to each other and between which cartridges are placed, and a member providing a bottom upon which said cartridges rest, said member being formed with recesses at the portions opposite the caps of 105 the cartridges.

3. In a cartridge holding magazine, a base member, a plurality of tongues mounted upon said base member and between which the cartridges are adapted to be 110 placed, said tongues being inclined toward the center of said base member so as to hold said cartridges in the magazine in conical formation.

4. In a cartridge holding magazine, a 115 base, a plurality of tongues mounted upon said base and between which the cartridges are adapted to be placed, said tongues being inclined toward the center of said base so as to hold said cartridges in the magazine 120 in conical formation, and a member providing a bottom upon which said cartridges rest and correspondingly inclined to support said cartridges in a conical formation, said last mentioned member being slideable relatively to said tongue for ejecting the cartridges from the latter.

5. In a cartridge holding magazine, a 125 base, a series of tongues projecting toward the base between which the cartridges are 130

adapted to be placed, a cartridge ejecting member slideable along the length of said tongues, a bearing surface carried by said ejecting member and opposing said base, and 5 a spring interposed between said bearing surface and base for normally holding the ejecting member in an ineffective position.

6. In a cartridge holding magazine, a base, a series of tongues projecting from 10 said base between which the cartridges are adapted to be placed, a member providing a bottom upon which said cartridges rest and slideable along the length of said tongues for ejecting said cartridges, a bearing surface carried by said member and extending below said base, and a spring interposed between 15 said bearing surface and base for normally holding said member ineffective against the ejection of said cartridges.

7. In a cartridge holding magazine, a base, a series of tongues projecting from 20 said base between which the cartridges are adapted to be placed, a member providing a bottom upon which said cartridges rest and slideable along the length of said tongues for ejecting said cartridges, a bearing surface carried by said member and extending below said base, a spring interposed between 25 said bearing surface and base for normally holding said member ineffective against the ejection of said cartridges, and a cap for

housing said cartridges and engageable with said member.

8. In a cartridge holding magazine, a 35 base, a series of tongues projecting from said base between which the cartridges are adapted to be placed, a member providing a bottom upon which said cartridges rest and slideable along the length of said tongues for ejecting said cartridges, and coöperative means on said ejecting member and tongues for preventing accidental or easy removal of said ejecting member from said base and tongues.

9. In a cartridge holding magazine, a base, a series of tongues projecting from 40 said base between which the cartridges are adapted to be placed, a member providing a bottom upon which said cartridges rest and slideable along the length of said tongues for ejecting said cartridges from said magazine, certain of said tongues being formed with longitudinal slots therein, and projections extending from said member into said slots 45 for limiting the movement of said member relatively to said tongues.

In testimony whereof I have hereunto set my hand in presence of two subscribing witnesses.

WILLIAM DE COURCY PRIDEAUX.
